O. R. HOGUE

BAG FOR VACUUM CLEANER PARTS

Filed Aug. 4, 1924

witness:

UNITED STATES PATENT OFFICE.

OLIVER R. HOGUE, OF CHICAGO, ILLINOIS, ASSIGNOR TO FEDERAL ELECTRIC COMPANY, OF CHICAGO, ILLINOIS, A CORPORATION OF ILLINOIS.

BAG FOR VACUUM-CLEANER PARTS.

Application filed August 4, 1924. Serial No. 729,877.

To all whom it may concern:

Be it known that I, OLIVER R. HOGUE, a citizen of the United States, and a resident of Chicago, in the county of Cook and State of Illinois, have invented certain new and useful Improvements in Bags for Vacuum-Cleaner Parts; and I do hereby declare that the following is a full, clear, and exact description thereof, reference being had to the accompanying drawings, and to the letters of reference marked thereon, which form a part of this specification.

This invention relates to a novel and improved bag for vacuum cleaner parts and accessories, and consists of the matters hereinafter described and more particularly pointed out in the appended claim.

A vacuum cleaner apparatus in addition to the main casing or shoe and long handle, which as an assembled device is used as a sweeper, also includes many accessories and parts adapted to be attached when cleaning curtains, chairs, sofas, divans and the like, which being of unequal size and of awkward dimensions are apt to be mislaid and lost and thus never at hand when required for use.

The object of the present invention is to provide a bag or container of simple and economical construction and having suitable pockets to receive and hold the several most usual parts or accessories included with a vacuum cleaner. These parts in general comprise a long flexible tube and several hard tubes, one of the latter being quite long and the others much smaller, and other metal parts and attachments designed for attachment when the cleaner is used for other purposes than for cleaning floors, rugs and carpets. The improved bag may be hung on the inside of a closet door and the parts contained will always be at hand and readily accessible when they are required.

In the drawings:

Fig. 1 is a perspective view of the bag embodying the invention with the parts and accessories which it is adapted to contain shown in dotted lines in their respective pockets in the bag.

Fig. 2 is a horizontal section through the bag in a plane indicated by lines 2—2, Fig. 1.

Fig. 3 is a detail cross sectional view on an enlarged scale in a plane indicated by lines 3—3 of Fig. 1.

Referring now to that embodiment of the

invention illustrated in the drawings: 10 indicates the new bag. Said bag is made of any suitable tough, flexible material, such as canvas and consists of a vertical, elongated flat tubular pocket 11, closed at the bottom end 12, at the sides 13, 14 and open at the top. At one side of the bag—as illustrated at the righthand side, 14—is provided an elongated, transversely round tubular pocket 15, which extends from the bottom to the top of the bag and which forms the closure for the main pocket 11 at the said one side.

The main pocket 11 is adapted to contain the comparatively long flexible tube (indicated in dotted lines at 16) which is one of the most awkward accessories to be taken care of, when said tube is wound into the form of a flat spiral as shown. When wound in this way, the elongated pocket 11 is of just the size and shape to receive the said tube. The elongated pocket 15 is adapted to contain the usual long hard tube (indicated in dotted lines at 17), which is the largest hard tube accessory in apparatus of the kind.

The parts of the bag thus far described are readily and preferably made of three pieces, namely: a back piece 18, a front piece 19 and a side piece 20. The two pieces 18, 19 are secured flat together along the side 13 and the bottom 12,—a hem being turned at the edge of each piece to reinforce the side edge and bottom in a familiar manner. The front piece 19 is made wider than the back 90 piece 18 to provide an extension 19^a which is bent back (as shown in Fig. 2) and secured at its outer lateral margin to the margin of the back piece 18,—thus forming one side of the round tubular pocket 15. The 95 side piece 20 is made from a narrow piece which is adapted, with the part 19^a of the front piece, to form the tubular pocket 15. Said piece is secured at its lateral margins to the margins of the piece 18 and of the main 100 body of the piece 19. The margins are hemmed and sewed flat in a familiar manner at the bottom edge 12, and the stitching is carried clear across the flat, folded bottom end of the part 19^a and of the strip 20, thus 105 closing the bottom of the main pocket 11, and the bottom of the narrow, tubular pocket 15.

21, 22, 23, 24, indicate pockets attached to the front member 19 of the bag in a line 110

near its bottom end 12. Said pockets are of varied sizes,—21 and 22 being provided for short hard tubular parts (indicated in dotted lines at 21^a and 22^a), and the pockets 5 23 and 24 being provided for flat small metal parts (as indicated respectively at 23^a and 24^a.)

The said pockets 22 to 24 inclusive are made by means of pieces of fabric cut to 10 proper size and sewed or other wise conveniently attached to the front member of the main pocket in the manner of so-called patch pockets on a man's coat. Above the series of pockets just described is also provided a 15 side pocket 25, which is made and attached in like manner to those above described.

For suitably hanging the bag on a door or other upright wall, I provide at the top at each side, short tabs 26, 27, made of fabric or other flexible material, which are sewed or otherwise attached to the rear member 18 of the bag. A third tab 28 is attached to the bottom edge 12 of the bag. 20 By means of these tabs, the bag may be suitably suspended by hooks or nails on the inner face of the door or against a wall and may be held from swinging away from the 25

door or wall by the tab 28 at its bottom.

The many advantages of the novel bag and its utility for the purpose intended will be 30 understood and appreciated by any housewife who heretofore has been generally limited in the use of a vacuum cleaning apparatus to the cleaning of floors, rugs and carpets because of the loss or the mislaying of 35 the parts and accessories of the apparatus required in use for other purposes.

I claim as my invention:

A bag for vacuum cleaner parts and accessories, said bag being made of tough flexible 40 material and comprising a main flat tubular pocket of substantially the vertical and lateral dimensions of the bag, an elongated tubular pocket at one side of and forming the closure at one lateral edge of the main pocket, a 45 plurality of flat pockets attached to the front member of the main pocket, and suspension tabs for said bag, one at each side of and at the top of the rear member of the main bag and one at the bottom of the bag. 50

In testimony that I claim the foregoing as my invention, I affix my signature this 31st day of July, A. D. 1924.

OLIVER R. HOGUE.
